EARL S. GOMES
INVENTOR.

BY *James H. Rander*

ATTORNEY.

UNITED STATES PATENT OFFICE

EARL S. GOMES, OF CINCINNATI, OHIO

SHIPPING CARTON SUPPORT

Application filed September 1, 1931. Serial No. 560,545.

This invention relates to shipping cartons broadly and more particularly to a novel support, preferably used in connection with the carton to protect merchandise, such as 5 radio cabinets and the like, when shipped in said cartons.

The main objects of the invention are to provide a top support for radio cabinets which is simple, economical to manufacture, easily 10 installed within or removed from the carton and easily knocked down for shipping purposes.

A further and more detailed object of the invention is to provide a top support for a 15 shipping carton (preferably made of fibreboard) which is composed of a minimum number of parts, namely, a rectangular frame and an endless flexible band passed therearound.

A still further object of the invention is 20 to provide a top support for fibreboard shipping cartons which will space the merchandise to be shipped from the walls and top of the carton to guard against damage to the merchandise when being shipped.

25 My invention consists in providing a substantially rectangular frame having an endless band or web of paper passed over and embracing two sides of said frame and of sufficient length to conform with the top of radio cabinets and thereby hold said cabinets 30 within a fibreboard shipping carton in a manner to prevent damage thereto during shipment.

35 My invention further consists in the construction, combination, location and arrangement of parts, all as will be hereinafter more fully set forth and finally claimed.

40 Before proceeding with a detailed description of the invention, it is deemed desirable to point out the pronounced advantages of my invention in its contemplated application to a fibreboard shipping carton.

In shipping radio cabinets, and particularly 45 cabinets of the midget type now manufactured, difficulty arises in packing the cabinet in the carton due to the irregular shapes of the tops.

50 A large percentage of radio cabinets have dome-shaped tops or tops of various shapes, but generally converging towards a point,

and flat bases, and, due to this type cabinet the manner in which it is packed within a fibreboard shipping carton plays an important part in the condition it reaches its destination.

55 Heretofore various ways have been attempted in packing the rounded top midget radio cabinets to protect them and guard against damage in shipment by the use of numerous pads bent upon themselves and folded against the cabinet, but the disadvantage with all top supports, to the best of my knowledge, is that they are made of an excessive number of parts, or with an excessive number of 60 scores, which are difficult to insert within the 65 carton and thus consume considerable time in packing the carton and, further, that in such top supports the pads do not prevent shifting of the cabinet within the carton and, therefore, are liable to scratch or mar the finished surface of the cabinet and the weight of the cabinet is not evenly distributed which results in excessive strain on the cabinet and, as many of these cabinets are of comparatively 70 delicate construction, consisting of thin wood 75 glued and nailed together, I have found it desirable to evenly distribute the weight of the cabinet on the top support and in such a manner that the cabinet is prevented from shifting from side to side or from front to 80 rear within the carton so as not to come into contact with the carton.

85 It is a common practice to place an oiled or waxed paper over the cabinet, and with my improved top support this paper is not disturbed as it has no folded or bent flaps which are liable to be difficult in inserting within the carton and thus tear the oiled or waxed paper.

90 In the drawings:

Fig. 1 is a top view of a fibreboard shipping carton with the top closure flaps shown in open position to illustrate the position and manner in which the invention is placed therein;

95 Fig. 2 is a perspective view of the rectangular frame of the top support showing by broken lines the endless paper band or web placed over the ends thereof;

100 Fig. 3 is a central vertical section through

a fibreboard shipping carton, improved top support and a bottom tray used in connection with packing radio cabinets, the cabinet being shown in front elevation;

5 Fig. 4 is a perspective view of the bottom tray shown in section in Fig. 3;

Fig. 5 shows by side elevation a modification of the top support; and

10 Fig. 6 is a perspective view of the endless band or web of paper.

In the embodiment of my invention as illustrated and which shows a preferred construction I provide a support for shipping cartons comprising, generally, a rectangular frame 1 and an endless band or web of paper 2. As shown in Fig. 2, the frame 1 is composed of side walls 3 and 4 and end walls 5 and 6 with open top and bottom. The free edge of the side wall 3 is integrally attached to the free edge of the end wall 5 by an adhesive strip or tape 7. This frame is formed preferably from a blank of fibreboard which is scored or provided with weakened zones at 8, 9 and 10, respectively. Due 20 to this construction of the frame it can be collapsed for shipping purposes from the manufacturer to the consumer—that is to say, the end wall 5 can be folded against the side wall 4 and the end wall 6 folded against the side wall 3. The endless band or web 2 is preferably made from a strip of paper, the ends 11 and 12 being overlapped and adhesively secured together, as shown in Fig. 3. For medium sized shipping cartons 25 and for large shipping cartons the ends 11 and 12 can be overlapped a greater distance, as shown in Fig. 6, to provide a double thickness band throughout approximately one-half of its length. The frame 1 and endless band 2 comprises the subject-matter 30 of the present invention, but in order to explain its use in connection with a fibreboard shipping carton, attention is directed to Figs. 1 and 3 wherein 13 represents a shipping carton, which carton is composed of end walls 14 and 15, side walls 16 and 17, top closure flaps 18 and bottom closure flaps 19. 35 20 designates a packing tray which is formed from a blank of fibreboard and supplied with side flaps 21 and 22 and end flaps 23 and 24, the end flaps being further provided with short tabs 25 which are folded against the outer faces of the side flaps 21 and 22, as clearly illustrated in Fig. 4. Side flap 22 40 50 may be further provided with cut outs 26 to receive the control knobs 27—27 of a radio cabinet 28, shown in Fig. 3.

In packing an article of merchandise, such as the radio cabinet 28 shown in Fig. 3, the bottom closure flaps 19 of the carton 13 are glued or otherwise held shut and the packing tray 20 bent, as shown in Fig. 4, to receive the flat base 34 of the cabinet 28, the control knobs 27, as before stated, being received within the cut outs 26 in the side flap

22. The packing tray 20 and cabinet 28 are then inserted within the open top of the carton 13 and the cabinet lowered within the carton to the position shown in Fig. 3. The next step in packing the cabinet 28 within the carton 13 is to pass the endless flexible band 2 over the ends 5 and 6 of the frame 1, as shown by dotted lines in Fig. 2, and then place said frame and band over the domed-top 30 of cabinet 28, as shown in Fig. 3 75 and press downwardly on the frame until the end walls 5 and 6 of said frame draw the endless band 2 taut over the dome top 30 of the cabinet 28. Then close the top flaps 18 of carton 13 and secure them shut 80 by glue or in an equivalent manner.

In Fig. 5 I have shown a modification of the frame 1, which consists in providing the end walls with a clearance notch 31. In some types of radio cabinets a molding or 85 beading 32 protrudes beyond the surface 33 of the cabinet 29 and in order that the frame 1 may properly draw the web or band 2 taut over said surface it is necessary to provide the notch 31 in the end walls of the collapsible 90 frame, as above described.

In radio cabinets of the type illustrated in Fig. 3, the outer surface 33 is usually of bent wood and is strengthened from the inside of the cabinet by glued braces (not shown). 95 With my improved top support, any strain or weight upon the top flaps 18 of the carton 13 is evenly distributed over the dome portion 30 of the cabinets 28 and 29 and the greater the strain or weight upon said top flaps 18 the more the end walls 5 and 6 of the frame 1 and endless band 2 hug or bear inwardly 100 upon the surface 33 of cabinets 28 and 29 to thereby force said bent wood surface 33 towards its inner supports. 105

In other top supports for radio cabinets of the type described any weight or strain on the domed top 30 tends to tear or loosen the bent wood surface 33 from its inner supports which results in a damaged cabinet.

110 While I have shown and described one particular embodiment of my invention it is to be understood that certain changes and modifications can be made without departing from the scope or spirit thereof as defined in the claims.

Having thus described my invention, what I claim as new and desire to secure by Letters Patent is:

1. In combination with a shipping carton, a frame having open top and bottom, a flexible endless band surrounding said frame and extending across said open top and bottom and of sufficient length to yield within said frame when the latter is placed between the carton and an article packed therein whereby said article is securely held and protected from damage. 125

2. In combination with a shipping carton, a rectangular frame having open top and bot-

tom, a flexible endless band surrounding said frame and extending across said open top and bottom and of sufficient length to yield within said frame when the latter is placed between the carton and an article packed therein whereby said article is securely held and protected from damage.

3. In combination with a shipping carton, a frame having an open bottom, a flexible band surrounding said frame and extending across said open bottom and of sufficient length to yield within said frame when the latter is placed between the carton and an article packed therein whereby said article is securely held and protected from damage.

4. In combination with a shipping carton, a frame having an open bottom, a band extending across said open bottom and of sufficient length to yield within said frame when the latter is placed between the carton and an article packed therein whereby said article is securely held and protected from damage.
